UNITED STATES PATENT OFFICE.

PAUL PRATT, OF HACKENSACK, NEW JERSEY.

STENOGRAPHER'S NOTE-BOOK HOLDER.

1,271,219.

Specification of Letters Patent.

Patented July 2, 1918.

Application filed December 28, 1916. Serial No. 139,268.

To all whom it may concern:

Be it known that I, PAUL PRATT, a citizen of the United States, and a resident of Hackensack, in the county of Bergen and 5 State of New Jersey, have invented a new and Improved Stenographer's Note-Book Holder, of which the following is a full, clear, and exact description.

This invention relates to a note book or 10 copy holder adapted to be used by stenographers, whereby the book will be held in a convenient manner while transcribing notes on a typewriter.

The invention has for its general objects 15 to improve and simplify the construction and operation of devices of this character so as to be reliable and efficient in use, comparatively inexpensive to manufacture, and so designed as to hold a note book in such 20 a manner that the leaves can be easily and quickly turned and properly held.

The invention has as a further object to provide a novel arrangement of spring 25 clamps for holding the book and leaves, such clamps being so designed as to enable the book to be easily detached when required.

With such objects in view, and others which will appear as the description proceeds, the invention comprises various novel 35 features of construction and arrangement of parts which will be set forth with particularity in the following description and claims appended hereto.

In the accompanying drawing, which 35 illustrates one embodiment of the invention and wherein similar characters of reference indicate corresponding parts in all the views,

Figure 1 is a side view of the note book 40 holder shown in use;

Fig. 2 is a perspective view of the holder;

Fig. 3 is a plan view of the book and page-holding clamps.

Referring to the drawing, A designates 45 the frame or body of the holder, which comprises a standard made of upper and lower sections 1 and 2, and a cross head 3 on the upper end of the upper section, there being a hinge joint between the sections. This 50 joint is formed by one section being formed with a recess and split longitudinally to constitute two clamping jaws 4, and the other section has a tongue 5 which enters between the jaws, and a clamping bolt 6 passes through the jaws and tongue to enable 55 the sections of the standard to be

clamped rigidly together by tightening the bolt, or to be loosely pivotally connected by unloosening the nut of the bolt. The standard has its lower end mounted in a base 60 piece 7 which can be directly screwed to the top of a typewriter desk B centrally behind the typewriter C, or the base piece 7 can be screwed to an attaching spring plate 8 which has a spring-engaging member 9 extending rearwardly upwardly from the front edge of the plate 8, so that the attaching device can be inserted under the typewriter frame between the latter and the desk, the spring 9 being provided with a 65 longitudinal groove 10 which interlocks with the typewriter frame. In inserting the attaching device the spring 9 yields downwardly until the frame alines with the groove 10, when the groove interlocks 70 with the frame.

The head 3 has on its left end, front, rear and top spring or other clamps 11, 12 and 13 made and secured in any suitable manner. The front clamp 11 cooperates with the head 80 to grip the back cover 14 of a note book D, while the rear clamp 12 cooperates with the head 3 of the holder to clamp the rear cover 15 or the turned back leaves 16 of the book. After the book is thus adjusted in the holder 85 the leaves as they are successively turned are engaged under the top clip or clamp 13 so as to keep these leaves turned back. The clips 11 and 12 serve to firmly hold the book in place, while the upper clip 13 holds 90 those leaves back which have been turned after the book has been applied to the holder. To prevent the front or unturned leaves from moving by the wind, a vertical spring clamp 17 is fastened to the lower end 95 of the upper section 1 of the standard so as to engage the free ends of the unturned leaves, as shown.

Since the copy holder is positioned directly behind the typewriter it is necessary 100 to provide means for preventing the paper feeding out of the typewriter from covering the note book. For this purpose the pivot or bolt 6 has applied to it a forwardly extending curved arm 18 which has its forward end disposed in such a position that the paper as it feeds from the typewriter will engage under the arm and be deflected 105 downwardly thereby.

From the foregoing description taken in 110 connection with the accompanying drawing, the advantages of the construction and

method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A copy holder of the class described including a standard, a cross-head on the standard in the form of a bar, a pair of clamping members arranged respectively at the front and rear of the standard and tensioned normally to engage therewith to hold the front and back leaves of the copy, and a member carried by the cross head and arranged above the clamping members to engage over the turned-back leaves of the copy, all of said members being fastened to one end of the cross-head.

Copies of this patent may be obtained for five cents each, by addressing the "Commissioner of Patents, Washington, D.C."

2. A copy holder comprising a supporting structure having a horizontal bar and three members mounted on the left end of the bar and extending toward the right, two of the members being disposed respectively at the front and back and tensioned normally to engage the bar and being independently movable, and the third member being disposed over the bar and between the first-mentioned members, the free ends of the members being adjacent the middle of the bar.

3. A copy holder comprising a support, a pair of clamps fastened to the left portion of the support and extending toward the right and terminating with their free ends adjacent the middle of the support, said clamps being normally tensioned to engage the support, and a member fastened to the same portion of the support and extending over the top thereof with its inner end terminating adjacent the middle of the support.

PAUL PRATT.
